UNITED STATES PATENT OFFICE.

RUSSELL R. COES, OF WORCESTER, MASSACHUSETTS, ASSIGNOR OF ONE-HALF TO COES WRENCH COMPANY, OF WORCESTER, MASSACHUSETTS, A CORPORATION OF MASSACHUSETTS.

WRENCH-HANDLE.

1,357,848.

Specification of Letters Patent.

Patented Nov. 2, 1920.

Application filed July 24, 1919. Serial No. 312,923.

To all whom it may concern:

Be it known that I, RUSSELL R. COES, a citizen of the United States, residing at Worcester, in the county of Worcester and 5 State of Massachusetts, have invented certain new and useful Improvements in Wrench-Handles, of which the following is a specification.

My present invention relates to a novel 10 construction in metal handles for screw-wrenches, as more particularly hereinafter set forth; one object being to provide a wrench of the character described, with an all-metal handle of economic construction 15 provided with a plurality of scallops or finger-receiving corrugations along its edge, which smoothly merge with the non-corrugated side surfaces of the handle, the several parts being constructed and combined 20 substantially as hereinafter more fully explained.

A further object is to provide a wrench-handle comprising a handle frame having its longitudinal edge-embracing members integrally connected by a plurality of outstanding transversely arched braces or cross-tie members at the opposite sides of the shank-receiving space; said frame provided 25 with protuberances and depressions along its edge, in coinciding relation to said braces; and an exterior grip surface or shell consisting of comparatively thin wrought-metal tubing of uniform gage, mounted upon said frame and permanently compressed thereon, forming a plurality of 30 prominences and intervening depressions along the edge of the handle.

These objects I attain by a wrench-handle construction substantially as explained in 40 the following detailed description, and illustrated in the accompanying drawings, wherein Figure 1 represents a side view of a screw-wrench embodying my invention. Fig. 2 is a longitudinal section of the handle as assembled upon the wrench-bar shank. Fig. 3 is a side view of my improved wrench-handle frame separate from other parts. Fig. 4 represents a cross-section of tubing such as employed for forming the exterior 45 grip surface of the handle. Fig. 5 is a transverse section at line X X on Fig. 1.

Fig. 6 is a transverse section at line Y Y. Fig. 7 is a bottom end view of the handle, and Fig. 8 is a sectional view showing a modification in the arrangement of the tip. 55

In the drawing, Fig. 1, the numeral 1 indicates the bar of the wrench and 2 the wrench-bar shank; which bar and shank are formed substantially as heretofore employed; the shank having flat sides and 60 parallel longitudinal edges transversely rounded.

F indicates the cast-metal handle frame, which in accordance with my present invention is preferably made in the peculiar 65 skeletonized form illustrated, and comprises the neck-supporting ferrule 3, with the usual bearing-step 4 for the jaw-adjusting screw S; front and rear longitudinal shank-embracing edge-members 5, and tip-end disk 70 6, integrally united with the ferrule 3 by said members 5, the inner faces of which fit against the edges of the bar-shank 2 and have firm support thereon, while the ferrule embraces the neck of the bar and fits 75 firmly up against the shoulder 11, as heretofore employed. An opening is formed in the end-disk 6 for the reception of the reduced end 8 of the shank.

Upon the outer edge of the handle-frame, 80 below the ferrule or screw-bearing step, I provide, along the shank-embracing member 5, a plurality of protuberances 9⁺ and depressions or concavities 10⁺; the latter presenting, longitudinally, inwardly curved 85 surfaces between the protuberances; and having, laterally, a convex or rounded form. The two longitudinal members 5 are integrally united at intervals across each side of the shank-receiving space by narrow 90 transverse braces or laterally outstanding cross-ties 12 severally disposed in substantially coincident alinement with the protuberances 9⁺, and having open intervening spaces 13 between the several cross-ties, as 95 best shown in Fig. 3. The inner surfaces of the cross-ties seat flatly against the sides of the wrench-bar-shank 2, and their outer edges are rounded or arched to correspond with the cross-section shape of the handle. 100

The central cross-tie is preferably reinforced, as at 14, and provided with a recess

15 to accommodate the key or pin 16 that is inserted through the shank for securing the handle frame thereon.

The periphery of the end-disk 6 is best 5 rounded or beveled off at its outer angle, with or without a slight shoulder, as 7.

The grip-face or exterior member 20 of 10 the handle is made of a single straight section of comparatively thin wrought-metal drawn or welded tubing of uniform thickness, preferably of No. 12 gage, more or less, which may be cut to the required 15 length; said tubing being of a caliber that will conveniently fit over the exterior contour of the handle-frame and be supported by the peripheral surfaces of the cross-ties 20 12, and disk 6, and the end of the ferrule 3, which latter is best reduced, as at 18, to accommodate the thickness of the tube metal.

The handle-frame F, which may be of cast 25 metal, is formed with protuberances 9⁺ and depressions 10⁺ along its edge, and with the transverse cross-ties 12 coinciding in their 30 relation with the protuberances; the intervening spaces 13 relatively coinciding with the depressions 10⁺; the lower end 18 of the ferrule, the end-disk 6 and exterior contour of the cross-ties being of approximately 35 similar diameter and rotundity. The interior of this handle-frame is formed or broached out to a size of opening that will closely fit upon the shank 2. After placing the sliding jaw J upon the bar, said handle-frame is assembled upon the wrench-bar shank, against the shoulder 11 and the key-pin 16 driven tightly into place, said key-pin being a well known form of fastener. The reduced end of the shank is also riveted 40 at the outside of the end-disk, as at 8.

The exterior grip-face member or wrought-metal tubing 20, of the character specified, 45 cut to proper length, is arranged upon the exterior of the handle-frame, the upper end of said tube abutting against the ferrule, or fitting a shoulder formed thereon, as at 18. Said tube extends straight across the depressions 10⁺, but rests upon the protuberances 9⁺ and the outer edges of the cross-ties or 50 braces 12.

This exterior grip-face shell or tubular member 20 is compressed firmly and rigidly upon the exterior of the supporting members of the handle-frame, and portions of 55 the tube between the protuberances 9⁺ are sunken into the depressions 10⁺, thereby affording a plurality of permanent transversely disposed finger-receiving corrugations 10 and ridges 9 along the front edge of 60 the handle, below the projecting screw-bearing step; said corrugations laterally diminishing and smoothly merging with the plain non-corrugated surface of the grip at the respective sides of the handle, as best shown 65 in Figs. 1 and 5. Also, the lower end of the

tubular member is curled inward, as at 26, and crimped firmly against the rounded or beveled periphery of the integrally attached end-disk 6, meeting the shoulder 7, (see Figs. 2 and 7) thereby making a neat end 70 form which can be readily finished or polished as desired. My above described invention produces a very convenient, efficient and desirable wrench construction which can be manufactured with practical facility 75 and economy.

In some instances it may be desired to have a tip-end member separate from the handle-frame; therefore in Fig. 8 I have indicated a form of construction that may be 80 employed therefor in that instance. The handle-frame and tubular grip with corrugated front edge is practically the same as above described, but a separate tip-piece 23 is employed and the end of the tube 20 abuts 85 against the rim of said tip-piece, instead of being crimped in at the extremity of the disk.

I claim as my invention and desire to secure by Letters Patent—

1. A wrench handle including a skeletonized handle-frame comprising longitudinal bar-fitting edge members united by shank-embracing collars at the end, and a plurality of transversely disposed outstanding 95 cross-tie members, with intervening spaces between them; in combination with a thin-metal exterior grip-face-shell internally supported rigidly upon said outstanding members, and having portions of the shell permanently depressed or sunk into the intervening spaces upon said handle-frame, substantially as set forth.

2. A wrench-handle for adjustable screw wrenches of the character described, having 10 a projecting screw-supporting-step at its upper end with a full oval neck, that part of the handle below the projecting screw-supporting-step and neck being incased with a thin tubular shell of wrought metal provided with finger-receiving corrugations at 11 its front edge, and its opposite edge and sides formed approximately plain and longitudinally straight, the upper end of said shell abutting against and fitting around an offset at the neck with a close flush junction at a position approximately coincident with one of the protuberant portions of the corrugations, the under curve of the screw-supporting-step serving as a limiting curve for 12 the adjacent finger-receiving space.

3. A wrench-handle including a straight tubular handle-grip member of tubular wrought metal, the front edge of it provided with a plurality of transversely disposed 13 concave depressions that gradually merge with the straight uniform surface of the grip at the sides of the handle, and an internal support for said tubular grip-member including longitudinal embracing-members 14

and narrow protuberant transverse braces positioned thereon in intermediate relation to said depressions, and having the tubular grip-member engagingly compressed upon 5 said braces.

4. In a wrench, a metal handle-frame provided with a plurality of transversely disposed ridges and intervening recesses, in combination with an external grip surface 10 consisting of a piece of wrought metal tubing of uniform gage and caliber mounted upon said frame, and having portions thereof compressed into said intervening recesses, thereby presenting a series of smooth trans- 15 verse corrugations upon the exterior of the handle, for the purpose set forth.

5. In a wrench of the class described, a handle-frame having corrugations along its front edge-member, and transverse integral 20 cross-connecting members located to approximately coincide with the protuberant parts of said corrugations at the edge of the frame, the exterior of said cross-connecting members conforming to the cross-section 25 shape of the handle, and an external grip-member consisting of a section of wrought-metal tubing of uniform gage, rigidly fitting upon the exterior of said handle-frame and internally supported by the edge members, 30 and cross-connecting members thereof, portions of said tubing being bent inward to approximately conform to the corrugations on said handle-frame.

6. In a wrench of the character described, 35 a wrench-handle-frame having oppositely disposed edge-embracing members, and a tip-end disk formed integral with the edge-embracing members of said handle-frame, and an outer grip-forming shell of wrought 40 metal tubing mounted rigidly upon the handle-frame and having its outer end com-

pressed and crimped inward solidly about the periphery of said tip-end disk.

7. In a wrench of the class described, a handle-frame having protuberances and de- 45 pressions along its edge, and transverse integral connecting members located to approximately coincide with the protuberant parts at the edge of the frame with predetermined spaced intervals, the exterior of said 50 connecting members conformed to the cross-section shape of the handle; and an exterior member formed of wrought-metal tubing of uniform gage, fitting upon and internally supported by the frame and cross members 55 thereof, and said tubing pressed into the depressions along the edge of the handle-frame, and its outer end inwardly upset against the outer end of the handle-frame.

8. In a screw-wrench, in combination with 60 a wrench-bar-shank having flat sides, longitudinally parallel edges and a reduced tip-end, a handle-frame including the ferrule with a screw-supporting step, longitudinal edge-embracing members, one of which is 65 externally corrugated with protuberances and depressions, said members integrally united by a series of transverse externally arched cross-ties and by a tip-end disk having a rounded or inclined periphery and a 70 central opening, said wrench-bar shank fitting the interior of said handle-frame, its end in said central-opening, and an external shell of light metal tubing of uniform gage, mounted upon said frame and conformed 75 into the depressions at the corrugated edge of the frame, and the extreme lower end of said tube crimped inward about the periphery of said tip-end disk.

Witness my hand this twenty third day 80 of July, 1919.

RUSSELL R. COES.
